UNITED STATES PATENT OFFICE.

JESSE G. POPPERT, OF MILWAUKEE, WISCONSIN.

ELECTRICAL GAS-LIGHTER.

SPECIFICATION forming part of Letters Patent No. 708,398, dated September 2, 1902.

Application filed January 7, 1902. Serial No. 88,815. (No model.)

To all whom it may concern:

Be it known that I, JESSE G. POPPERT, a citizen of the United States, residing at Milwaukee, county of Milwaukee, and State of Wisconsin, have invented new and useful Improvements in Electrical Gas-Lighters, of which the following is a specification.

My invention relates to improvements in electrical gas-lighters.

10 The object of my invention is to provide a form of mechanism which may be conveniently operated by pressure of the thumb or finger of the hand in which the device is held.

15 In the following description reference is had to the accompanying drawings, in which—

Figure 1 is a side view of my invention. Fig. 2 is a longitudinal sectional view drawn 20 at right angles to the push-button. Fig. 3 is a cross-sectional view on the line of the push-button.

Like parts are identified by the same reference characters throughout the several views.

25 A handle 1 is provided with a laterally-extending bushing 2, which constitutes a bearing for a push-button 3. A stationary rod 5 is inserted in the end of the handle 1, being preferably provided with a screw-threaded

30 end 6, which engages in a suitable socket in the handle 1 and bears against a spring 7 within the socket, as shown in Fig. 2. An axially-rotatable rod 8 is also inserted in the end of the handle, with bearings at 9 and in

35 a ferrule 10, which is screwed into the end of the handle, whereby the rod 8 is held in a position parallel to that of the rod 5. The outer end of the rod 8 is provided with a coiled spring 12, having one end extended to form

40 a yielding contact-arm 13, adapted to engage with and snap past the end of the rod 5, which is also preferably provided with a yielding or resilient tip 14, when the rod 8 is rotated. At or near the inner end of the rod 8 and within

45 the handle 1 a spring 15 is coiled around the rod 8, with one end secured to the handle and the other end looped around an arm 16, which projects laterally from the rod 8 in the path of the push-button 3, so that when the latter

50 is pushed inwardly the rod 8 is caused to rotate on its longitudinal axis against the tension of the spring 15, which when the push-button is

released reacts and restores both the button and the rod 8 to normal position. The arrangement is such that when the rod 8 is thus 55 oscillated or partially turned by pressure on the push-button the contact-arm 13 will engage with and snap past the end of the rod 5, this movement being repeated in the opposite direction during the spring reaction. 60 The rear end of the handle is provided with a cap 20, which incloses binding-posts 21 and 22, to which flexible conductors 23 and 24, passing through suitable apertures in the cap 20, are respectively connected. 65

25 and 26 are conductors leading from the binding-posts 21 and 22 to the springs 7 and 15, respectively, each spring and its respective conductor being preferably formed integrally of a single piece of wire. 70

Any suitable source of current-supply, such as the batteries 30 and sparking-coil 31, may be utilized.

It will be understood that the handle and push-button will be formed of gutta-percha 75 or other non-conducting material. The handle is preferably formed of two parts secured together at the rear end by a cap 20 and at the front end by a binding-ring 36, thus furnishing convenient means of separation for 80 examination or repairs of interior parts.

Having thus described my invention, what I claim as new, and desire to secure by Letters Patent, is—

1. An electrical igniter, comprising a handle; a laterally-extending push-button; a fixed electrode projecting from the handle; an axially-oscillating electrode, having a resilient arm adapted to engage the fixed electrode, and yieldingly pass the same; an arm 85 projecting from the oscillating electrode into the path of the push-button; a coiled spring located on the oscillating electrode with one arm secured to the handle, and the other engaged under the push-button arm of said 90 electrode; and electrical conductors leading from a suitable source of current-supply and electrically connected with said electrode; said handle being made in longitudinally-divided sections, adapted to inclose the inner 95 ends of the electrodes and the actuating spring of the oscillating electrodes. 100

2. An electrical igniter, comprising a handle; a fixed electrode having end-to-end con-

nection therewith; an oscillatory electrode, arranged for positive make-and-break contact with the fixed electrode; a push-button extending laterally from the handle, and having operative connection with the oscillatory electrode; a spring for retracting said electrode; flexible conductors connecting the electrodes with a suitable source of current supply; said oscillatory electrode being provided with suitable bearings in the interior

of said handle; and a ferrule connected with the handle and projecting therefrom to support said electrode exteriorly, and hold the same in position in the handle.

In testimony whereof I affix my signature 15 in the presence of two witnesses.

JESSE G. POPPERT.
